Attorney.

UNITED STATES PATENT OFFICE.

GEORGE HENDERSON, OF BOSTON, MASSACHUSETTS.

NIPPLE FOR EARTHENWARE CONTAINERS.

Application filed May 15, 1925. Serial No. 30,518.

To all whom it may concern:

Be it known that I, GEORGE HENDERSON, a citizen of the United States, residing at Boston, in the county of Suffolk and State 5 of Massachusetts, have invented certain new and useful Improvements in Nipples for Earthenware Containers, of which the following is a specification.

My invention relates to an improvement 10 upon the nipple described in my Letters Patent of the United States, No. 1,043,230, of November 5, 1912. It has been the special object of my invention to render more secure the means for mounting and holding 15 in position the lugs which embrace the inner surface of the earthenware container adjacent the aperture therein in which my nipple is mounted.

My device may be best understood by 20 reference to the accompanying drawings in which—

Fig. 1 is a side view cross-section of my device mounted in an earthenware container, a portion of which container is shown broken 25 away.

Fig. 2 is a bottom view of my device.

Referring now more specifically to the drawings, 1 is a cylindrical sleeve which is 30 screw threaded on its outer surface and which is provided in its lower portion with a cross-rod 2 which extends across the base of the sleeve 1 upon the diameter, being securely supported in opposite holes in the sleeve 1.

The sleeve 1 is adapted to fit closely within 35 in an annular hole in the surface of an earthenware container 3. Slidably mounted upon rod 2 are rectangular lugs 4 and 5 which are provided with holes in the upwardly extending portion thereof so that the lugs may be moved along rod 2. To insert the sleeve and lugs within the hole in the earthenware container, it is necessary to slide lugs 4 and 45 5 between each other so that they will meet near the center of the rod 2. After being passed through the opening in the container the lugs 4 and 5 may then be slid into the positions shown in Fig. 1 wherein they underlie the adjacent lower surface of the container 3.

A locking ring 6 is screwed about the outer threaded surface of the cylindrical sleeve 1. Beneath this locking ring 6 is a gasket 7, and upon screwing down the locking ring 6 a firm contact of the gasket 55 7 with the top of the container is made and at the same time the lugs 4 and 5 are drawn into firm engagement with the end surface of the container. Considerable stress is required to effect a firm joint. Such stress 60 has a tendency to slightly bend the rod 2 downwardly, particularly if the lugs 4 and 5 slip even slightly toward the center of the rod 2. I have found that it is very important to check such slipping as there 65 is increasing tendency to slip, once any slipping is developed. It is very important that the upwardly extending portions of lugs 4 and 5 be always maintained in close and even engagement with the inner surface of 70 the sleeve 1. Hence, I have provided a roughened surface for the rod 2 which is very effectively done by providing the rod 2 with a screw threaded surface. Such a surface will effectively prevent any slipping of the lugs 4 and 5 and will retain 75 the parts always in the desired position.

The top of the nipple is closed by the screw cap 7 within which is fitted a disc 8 made of rubber cork or other compressible 80 material so as to secure a tight closure. It will be readily understood that all parts of my device are made of metal, except the gasket 7 and the disc 8.

Having thus fully described my invention 85 what I claim is:

In a device of the character specified the combination of a sleeve arranged to be inserted in an opening in an earthenware container said sleeve being screw threaded upon its exterior, a roughened rod mounted in the lower portion of said sleeve and extending across the same, lugs slidably mounted on said rod, a threaded locking ring arranged to be screwed down upon said sleeve, 90 and a gasket beneath said locking ring.

In witness whereof I have hereunto affixed my signature.

GEORGE HENDERSON.
